UNITED STATES PATENT OFFICE.

WILHELM BRASE, OF BERLIN, GERMANY.

SEWING MACHINE.

Application filed October 12, 1923. Serial No. 688,250.

To all whom it may concern:

Be it known that I, WILHELM BRASE, a citizen of the German Republic, and resident of Berlin, Germany, have invented new 5 and useful Improvements in Sewing Machines, of which the following is a specification.

My invention relates to a machine in which cloth or other suitable material may 10 be provided with embroideries, festoon stitches, hemstitch or the like, and which work is done automatically under the control of a jacquard device. With my invention, I produce the backward and forward 15 stitches by shifting the fabric, and the side stitches by moving the needle and the parts cooperating therewith. By this arrangement, the fabric is prevented from lateral movements and is thus properly guided, 20 which is necessary, particularly when hemstitch or edge seams are produced. Owing to the use of only four kinds of stitches and combinations thereof, my jacquard device 25 needs only four adjustments, and the cam chain or perforated band actuating said jacquard device needs only four rows of 30 cams or perforations. The cam chain consists of a number of plates, preferably of sheet metal, formed with ribs in form of cams, according to the pattern to be produced, the plates being fastened to each 35 other by means of hooks or the like. For the purpose of feeding the fabric in a certain direction, I preferably use two fabric feeders, although a single feeder may be used, of suitable construction, one of said feeders 40 acting in forward direction and the other in backward direction.

Further I provide two presser bars, each 45 of which is formed with a separate presser foot, each of said feet being capable of acting independently of the other, and one of them being adjustably spaced relative to the other. In order to guide the fabric better, 50 when feeding in linear direction, I prefer to make the feet in form of combs.

In the accompanying drawing, in which 55 similar reference characters denote corresponding parts, Fig. 1 is a side elevation of the machine, part of the frame being cut

away; Fig. 2 is a plan view thereof; Fig. 3 is a vertical cross-section of the machine showing the parts actuating the fabric feeders; Fig. 4 is a vertical section on line A—A of Fig. 1; Fig. 5 is a vertical section on line B—B of Fig. 1; Fig. 5^a is an enlarged cross section of the machine showing the adjustment lever; Fig. 6 is a front view of the machine; Fig. 6^a is a side elevation of one of the fabric feeders; Fig. 7 is a vertical section on line D—D of Fig. 1; Fig. 8 is a longitudinal section on line C—C of Fig. 6; Fig. 9 shows a link of a pattern chain; Fig. 10 is a longitudinal section on line A—A of Fig. 9; Fig. 11 is a side elevation of the 65 chain carrying drum and of a part of the chain; Fig. 12 is a perspective view of a modified pattern chain; Fig. 13 is a front view of the lower part of the presser rods; Fig. 14 is a side elevation thereof; Fig. 15 is a plan view thereof; Fig. 16 is a front view of a modified presser foot; and Fig. 17 is a plan view thereof.

With reference to Figs. 1—17, the frame of the machine consists of the base plate 1 and the arm 2, the free end of which forms a head. Within the arm 2, bears the shaft 3 to the front end of which is attached the crank pin 4 (Fig. 8) adapted to reciprocate the needle bar 5 (Figs. 1 and 6) in vertical 80 direction and to operate a lever 7, one end 8 of which is pivoted in the head of the machine, and from the other end 9 of which is suspended a frame 10 (Figs. 1 and 6) from which the upper end of the needle bar 5 is suspended to be laterally slidably. By virtue of this arrangement, the needle bar 85 can move laterally, while reciprocated vertically.

The crank pin 4, at the same time, actuates 90 the thread-supplying mechanism 11, 12, which is of well-known construction and has the purpose of adapting, in well-known manner, the movements of the sewing thread to the sewing operation. The sewing thread 95 is taken from a bobbin 13 supported on a pin 13 carried by the arm 2. From this bobbin the thread passes over the well-known brake mechanism 14 and through an eye 15 of an arm 11 (Fig. 6) of said thread-sup- 100

plying mechanism. Then after passing through an eye provided in the end of an arm 16 extending from the needle bar 5, the thread passes through the eye of the needle 17. When the needle bar together with the needle moves laterally, this arm 16 is adapted to hold the thread between the eye 15 in the arm 11 and the eye in the arm 16 at as uniform a length as possible. The needle 17 is fastened, in well-known manner, to the needle bar 5 by means of a clamp 18 and the upper end of said bar is formed with an eye 19 slidably engaging a rod 20 carried by the frame 10 (Fig. 1).

15 The front of the head of the arm 2 is closed by a cover plate 21, to which the brake discs 14 are fastened. The thread-supplying lever 11 projects through a slit 22 (Figs. 6 and 8) provided in this cover plate 21. From the bobbin 13' the sewing thread passes through an eye 23 in an ear of the plate 21. In vertical direction the needle bar 5 is guided within a bore of the front portion 25 of a rectangular frame, the 20 rear end of which is pivotally connected by means of arms 26, 27 to the front portion of a frame 28, the rear part of which is pivoted at 29, 30 (Fig. 8) in the arm 2.

25 The front portion of the frame 28 is provided with a member 31 (Fig. 1) to which is connected a horizontal actuating rod 32. The lower end of the portion 25 is guided with a slit of a fork 25' fastened to the under side of the head of the machine. The rear end of the shaft 3 carries a strap disc 33. Mounted on said shaft 3, are further a cam disc 34, a crank 35, a cam disc 36, a cam disc 37 and alongside the latter a cog wheel 38 with which meshes a larger cog wheel 39 to 30 which is fixed a smaller cog wheel 40 (Figs. 1 and 3). Both wheels 39, 40 rotate on a pin 41 fixed in a bracket 43 (Fig. 2) of the arm 2. The bracket 43 carries also a second pin 44 on which is rotatively mounted a cog 45 wheel 45 meshing with the cog wheel 40, and to which is fastened the chain drum 46, so that the latter can be turned through the medium of shaft 3. The drum is of polygonal shape, so that a number of planes are 50 formed on which the links of the pattern chain may bear. At every revolution of the shaft 3, a plane of the drum 46 is turned in opposite direction to that of the actuating mechanism hereinafter to be described. The 55 stroke of the motion of the cog wheels 38, 39, 40 and 45 is to be arranged accordingly.

At the under side of the base plate 1, are arranged the cloth feeders and the shuttle mechanism.

60 The casing 47 (Fig. 8) for the oscillating shuttle of well-known construction is fastened to the front end of a tube or sleeve 48 slidably supported in bores of arms 49, 50 projecting downwardly from the under face 65 of the base plate 1. The shuttle shaft 51 is

borne within the sleeve 48 and carries at its rear end a crank 52 having a crank pin 53. Above and parallel to said sleeve 48 and the shuttle shaft 51, is arranged a fixed rod 54 on which is rotatably mounted, by means of a hub 55, a forked lever 56 (Figs. 4 and 8). The pin 53 of the crank 52 engages the slit of said forked lever 56. Connected to the latter with one end is further a forked lever 57, the other end of which is fulcrumed in the plate 1 at 57' (Fig. 4). Pivoted to said lever 57 is a connecting rod 58, the other end of which is connected to the crank 35 of the shaft 3 (Fig. 1). On turning the latter, the connecting rod 58 is reciprocated in vertical direction. The pin 53 of the crank 52 thereby receives at the same time oscillating movements, which by means of the shuttle shaft 51 are transmitted to the shuttle. At the same time, the shuttle casing and the shuttle with its cooperating parts are able to move in longitudinal direction of the machine, as the crank pin 53 is allowed to slide within the slit of the lever 56. Mounted between the arm 2 and the plate 1, 90 is a vertical rock shaft 59 (Figs. 7 and 8), from the upper end of which projects laterally an arm 60, to the end of which is connected the rod 32 (Fig. 1). Projecting from the lower end of said rock shaft 59, is a 95 similar arm 61, the end of which is connected by means of a connecting rod 62 to the sleeve 48 carrying the shuttle casing 47. In this manner, the needle 17 with its cooperating parts and the shuttle with its parts 100 are so connected to each other that both are caused to always move in unison in longitudinal direction of the machine.

These movements preferably are effected through the following mechanism:

105 Cooperating with the cam disc 37 of the shaft 3, is a fork 63 (Figs. 5 and 8) formed on the upper end of a rod 64. Immediately below said fork, the rod is provided with a lateral pin 65 adapted to engage a groove 110 66 of a rail 66, which by means of a pin 67 rotatively bears in the wall of the arm 2 (Figs. 5 and 8). Projecting from said rail 66 is an adjustment lever 68 (Figs. 5, 5a) 115 which is formed with a lock pin 68a cooperating with notches or holes 2a provided on a part projecting laterally from the arm 2. By slightly bending the lever 68 laterally its lock pin 68a becomes disengaged 120 from a notch 2a and by swinging the lever around the axis of the point 67, the groove and its rails 66 are capable of being adjusted into a more or less slanting position, so that the stroke of the vertical movements of the rod 64, when reciprocated by the rotation of the shaft 3, according to the position of said rail, will be made larger or smaller. The lower end of the rod 64 is joined by a ball and socket bearing 69 to an arm 70 projecting laterally from a shaft 71 arranged 125 130

transversely of the machine (Fig. 8). From the front end of this shaft 71, projects an upright arm 72 to the free end of which is connected an arm 73 (Fig. 1). Projecting from the upper end of the latter, is a knife edge 74. From the shaft 71 projects laterally an arm 75, the free end of which engages the slit of a fork provided in an arm 76 of equal length. This arm is arranged on a shaft 77 borne in the machine parallel to the shaft 71. The shaft 77 has an upright arm 78 of a length equal to that of the arm 72. To the end of the arm 78, is pivoted a member 79 provided at its free end with an upright knife edge 80. When the shaft 3 is rotated, the arm 70 oscillates vertically and correspondingly the arm 72 oscillates in horizontal direction, while the arm 78 performs equal movements but in opposite direction.

To the right-hand end of the connecting rod 32 is pivoted a member 81, the free end of which is capable of moving up and down and the lower face of which is formed with sharp teeth. By the pressure of a spring actuated bolt 82, the member 81 is kept in engagement with a stationary knife edge 83 (Fig. 1) fixed to the frame of the machine. Thereby the needle and shuttle are normally prevented from moving in longitudinal direction of the machine. The knife edges 74 and 80 are capable of moving below the teeth of the member 81.

When now the needle and its cooperating parts are to be reciprocated laterally step by step to produce a right-hand or left-hand stitch, then correspondingly either the knife edge 74 or the knife edge 80 must be temporarily raised. In order to produce a left-hand stitch, the knife edge 74 must be raised into engagement with the member 81, raising thereby the latter from the stationary knife edge 83. The knife edge 74 then moves to the left. At the completion of this movement, the knife edge 74 is lowered, so that the member 81 again bears on the stationary knife edge 83.

The operations hereinbefore described are indirectly controlled by a jacquard device to be hereinafter described.

In order to feed the fabric to be embroidered in sewing direction, I preferably provide two independently acting feeders, (Fig. 6). Each of said feeders comprises a plate 84 toothed on its upper face and the teeth of which project through a row of slits arranged in the stitch plate 85. Said teeth engage the fabric to be treated, and at the same time press the same against the presser foot or feet. Each plate 84 is attached to the free end of a member 87. The other end of one of these members is pivoted to two arms 88 projecting from a shaft 90 mounted in the base plate 1 parallel to the shuttle mechanism. The shaft 90, at its

right end, is provided with an arm 91 (Fig. 4) extending towards the middle of the plate 1 and to the end of which is connected a rod 92. The upper free end of said rod is formed to a fork 93, and the same cooperates with the cam disc 34 of the shaft 3. On turning the shaft 3, the fork oscillates to and fro. Below the fork extends laterally of the rod 92 a pin 93' engaging the groove of a rail 94. This latter is in form similar to the previously mentioned rail 66. By adjusting this rail 94 into the desired slanting position by means of an adjusting lever 95, the rod 92 receives corresponding vertical reciprocating movements, whereby by means of the arm 91 and the shaft 90 the corresponding feed member 87 is reciprocated. A shaft 96 (Fig. 6) parallel to shaft 90 supported in the plate 1 is provided with the upright arms 97, 98 (Figs. 1 and 6) carrying the second feed member 87. The shaft 90 is further provided with a downwardly extending arm 99 and the shaft 96 is provided with an upright arm 100. Both arms are connected with one another by means of a rod 101, so that the rotary movements of the shaft 90 are transmitted to the shaft 96 in opposite directions. Consequently both feed members move to and fro in opposite directions. When at rest, the teeth of said feed members are about level with the surface of the stitch plate.

In order to feed the fabric to be treated forward or backward by said feed members 87, it is necessary to raise one or the other feed member. When raised, the feed member presses the fabric against the presser foot or feet 86, which is or are thereby somewhat lifted. When the feed member is again lowered the presser foot presses the fabric against the stitch plate, and the fabric is thus prevented from moving.

The lifting of the feed member 87 in proper time is indirectly caused by my jacquard device preferably constructed as follows:

A pattern chain (Figs. 9-12) is guided by a drum 46. The chain is composed of a number of plates 102 preferably connected to each other by means of hooks or the like. The drum is provided with pins 103 engaging corresponding perforations 104 in the plates 102. From these plates project cams or teeth 105, which preferably are produced by pressing and whereby the plates receive a certain stiffness, so that they may be formed of comparatively thin sheet metal. Eight different kinds of plates are used in my machine, by which I can produce 115 stitches in forward, backward, right-hand and left-hand directions, and further in forward right-hand, forward left-hand, backward right-hand and backward left-hand directions. By a corresponding com- 120 125 130

1
bination of plates of the different kinds, pattern chains can be formed for the automatic production of embroideries, festoon stitches or hemstitches of the greatest variety of design. The plates may be made flat, as in Figs. 9-11 or be arched as in Fig. 12. For the latter kind, the drum 46 is made cylindrical.

Within the arm 2, I provide four pendula 106 (Fig. 3), each of which is provided at its lower end with a horizontal arm or bar 107, the outer end of which carries a roller 108. By means of springs 109, these rollers are forced against the pattern chain guided 15 by the drum 46. The other end of each bar 107 cooperates with one of four upright fingers 110. Each finger 110 is pivoted with its lower end to a lever 111. All four levers 111 are rotatably mounted on a shaft 112 20 supported in the frame of the machine. For the purpose of adjustment, each lever 111 has a finger 113 bearing against a set screw 114, four of which are provided at suitable places in the frame of the machine.

25 The cam disc 36 on the shaft 3 is mounted above the arms 110 and cooperates with a fork 115 of a lever 116 fulcrumed at 117 to the frame of the machine. On its lower face, said fork has a projecting ledge 118. 30 When the shaft 3 is revolved, the fork 115 receives oscillatory motion, so that when its projecting edge 118 is lowered, it engages one of the fingers 110, which by corresponding cams of the pattern chain have been 35 brought into its range, depressing said finger.

From the hubs of two of the levers 111 also project arms 119 provided at their free ends with rollers 120, which engage slits in 40 the arms 73 and 79, said arms 119 being drawn downward by springs 121 (Figs. 1 and 5). When while lowered, the ledge 118 of the fork 115 engages one of the fingers 110, the corresponding lever 111 is moved, 45 and its arm 119 pushes the knife edge 74 or 80 against the rack of the member 81. The same thereby is lifted from the stationary knife edge 83 and now the needle 17 with its cooperating parts is shifted laterally under the influence of the cam disc 37.

From the hubs of both other arms 111 project arms 121' (Fig. 3), which by rods 122 are connected to arms 123 provided on shafts 124 parallel to shafts 90 and 96 and 55 supported in the base plate 1 (Fig. 6). From the shafts 124, extend arms 125 towards the shuttle mechanism provided at their free ends with rollers 126 engaging slits in the members 87.

60 When now one of the previously mentioned fingers 110, influenced by a corresponding cam of the pattern chain, is shifted into the range of the ledge 118 and is depressed by the latter, the corresponding shaft 124 receives a rocking movement

through the arms 111 and 121', the corresponding rod 122 and the corresponding arm 123. Thereby the corresponding arm 125 lifts the corresponding member 87 by means of its roller 126. The feed member 84 thereby presses the fabric against the presser foot 86 and the latter, together with the fabric, is raised, and under the influence of the cam disc 34, the latter is fed one step. By presser springs 136 (Fig. 6) the feed members 87 are forced downward.

70 In my machine, I preferably provide two presser foot rods 127. Both are spring actuated, and they can be lifted independently by means of levers in well-known manner. 80 Preferably to one of the two rods (Figs. 13-15) a foot 86' is adjustably fixed, while the other rod 127 carries a foot 86, which can be laterally adjusted to be farther from or nearer the foot 86'. To this end, the corresponding rod 127 has fixed to it a plate 131 grooved at its back, as at 131' (Fig. 14), and provided with a longitudinal slit 131' for the passage of a fastening screw 133 carrying a nut 132. The opposite faces of the 90 plate 131 and of the upper part of the foot 86 are provided with fine teeth, as at 131'a, so that the foot will be securely held in position perpendicular to the surface of the stitch plate. The opposite edges of the feet 86, 86' are provided with notches or slits 134, 135 through which the embroidering needle is able to draw the thread from one foot to the other.

95 In case of using only one presser foot, or broad feet, I preferably construct said foot or feet 86'a in form of a comb, as at 86'b, as shown by Figs. 16 and 17.

What I claim is:—

1. In a sewing-machine, the combination 105 of a needle mechanism capable of moving across the sewing direction, a fabric feeding mechanism reciprocating to and fro in sewing direction, and a jacquard device indirectly controlling said needle mechanism and fabric feeding mechanism, as and for the purpose specified.

2. In a sewing-machine, the combination 115 of a needle mechanism capable of moving across the sewing direction, a shuttle mechanism operatively connected to said needle mechanism, a fabric feeding mechanism reciprocating to and fro in sewing direction, and a jacquard device indirectly controlling said needle and fabric feeding mechanisms, as and for the purpose specified.

3. In a sewing-machine, the combination 125 with driving means and a needle bar reciprocated thereby in vertical direction, of a laterally displaceable needle bar carrier, means for linearly guiding said needle bar carrier, a shuttle mechanism positively connected to the needle bar with reference to its sideward movements, means for feeding the fabric to and fro in sewing direction, 130

and a jacquard device indirectly controlling the lateral movements of said needle bar carrier and of said fabric feeding means, as and for the purpose specified.

- 5 4. In a sewing-machine, the combination with the driving means and a needle bar reciprocated thereby in vertical direction, of two guides pivoted together and of which one carries the needle bar, means for linearly guiding said needle bar carrying guide, a shuttle mechanism in cooperation with said needle bar, means operatively connecting the other guide to said shuttle mechanism, means for feeding the fabric in forward sewing direction, means for feeding the fabric in backward sewing direction, and a jacquard device controlling indirectly the lateral movements of the needle bar and the operating movements of the feeding means, as and for the purpose specified.

- 15 5. In a sewing-machine, the combination with the driving means and a needle bar reciprocated in vertical direction, of means for laterally moving said needle bar across the sewing direction, a shuttle mechanism operatively connected to said needle bar, means for operating said shuttle from said driving means, vertically and horizontally movable means for feeding the fabric in sewing direction, means for imparting the horizontal movement to said feeding means from said driving means, and a jacquard device indirectly controlling the lateral movements of said needle bar and the vertical movements of the feeding means, as and for the purpose specified.

- 30 6. In a sewing-machine, the combination with the driving means and a needle bar actuated thereby in vertical direction, of means for laterally moving said needle bar across the sewing direction, a shuttle mechanism operatively connected to said needle bar with respect to its lateral movements, means for driving said shuttle mechanism in cooperation with said driving means, vertically displaceable means for feeding the fabric in forward sewing direction, vertically displaceable means for feeding the fabric in backward sewing direction, means for horizontally reciprocating said feeding means in cooperation with said driving means, both said feeding means being operatively connected to move in opposite directions, and a jacquard device indirectly controlling the lateral movements of the needle bar and the vertical displacements of the feeders, as and for the purpose specified.

- 45 7. In a sewing-machine, the combination with the driving means and a needle bar actuated thereby in vertical direction, of means for moving said needle bar transversely of the sewing direction, a shuttle mechanism operatively connected to said needle bar with respect to its transversal movements, means for driving said shuttle

mechanism in cooperation with said driving means, means for feeding the fabric in forward sewing direction, means for feeding the fabric in backward sewing direction, both said means being operatively connected to move in opposite directions and being oscillated from said driving means, separate means for vertically moving each of said fabric feeding means, and a jacquard device indirectly controlling said last named means and the lateral movements of said needle bar, as and for the purpose specified.

8. In a sewing-machine, the combination with driving means and a needle bar actuated in vertical direction thereby, of means for moving said needle bar transversely of the sewing direction, a shuttle mechanism operatively connected to said needle bar with respect to its lateral movements, means for driving said shuttle mechanism in cooperation with said driving means, a thread-supplying mechanism in cooperation with said driving means, means for feeding the fabric in forward sewing direction, means for feeding the fabric in backward sewing direction, means connecting both said feeding means for effecting opposite movements, cam controlled means operatively connected to one of said fabric feeding means, means for adjusting the stroke of said last named means, separate means each actuating a fabric feeding means in vertical direction, and a jacquard device indirectly controlling said two last named means and said needle bar, as and for the purpose specified.

9. In a sewing-machine, the combination with the driving shaft and a needle bar actuated in vertical direction by said shaft, of a needle bar carrier capable of being shifted transversely of the sewing direction, a shuttle mechanism, a thread-supplying mechanism, a lever mechanism connecting said carrier and said shuttle mechanism with respect to their lateral movements, means for driving said shuttle mechanism in cooperation with said shaft, a member operatively connected to said carrier and to said shuttle mechanism, a stationary support normally engaging and supporting said member, two reciprocating members capable of temporary engagement with said first named member, means for imparting reciprocatory movements to said movable members from said shaft, means for feeding the fabric in forward sewing direction, means for feeding the fabric in backward sewing direction, both feeding means being connected to carry out opposite movements, a cam controlled means operatively connected to one of said feeding means, means for adjusting the stroke of said cam controlled means, means for actuating each fabric feeding means in vertical direction, and a

- jacquard device indirectly controlling said lever mechanism, the last named actuating means and said movable members, as and for the purpose specified.
- 5 10. In a sewing-machine, the combination with the driving shaft and a needle bar actuated in vertical direction by said shaft, of a needle bar carrier capable of being displaced transversely of the sewing direction, 70
- 10 a shuttle mechanism, a thread-supplying mechanism, a lever mechanism connecting said carrier and said shuttle mechanism with respect to their lateral movements, means for driving said shuttle mechanism 75
- 15 in cooperation with said shaft, a rack operatively connected to said lever mechanism and connecting the latter to said shuttle mechanism, a stationary knife edge normally engaging and supporting said rack, means for normally holding said rack and 80
- 20 edge in contact with one another, two movable knife edges capable of temporary engagement with said rack, two arms operatively connected to said movable knife edges, 85
- 25 said arms being connected to move in opposite directions, a cam controlled member connected to one of said arms, means for adjusting the stroke of said member, means for raising said movable knife edges, means 90
- 30 for feeding the fabric in forward sewing direction, means for feeding the fabric in backward sewing direction, a lever mechanism connecting both said feeding means to cause them to move in opposite directions, 95
- 35 cam controlled means operatively connected to one of said fabric feeding means, means for adjusting the stroke of said cam controlled means, two separate lever mechanisms, each actuating a fabric feeding means 100
- 40 in vertical direction, and a jacquard device indirectly controlling said means for raising said movable knife edges and all said lever mechanisms, as and for the purpose specified.
- 45 11. In a sewing-machine, the combination with the driving shaft and a needle bar actuated in vertical direction by said shaft, of a needle bar carrier capable of being displaced transversely of the sewing direction, 105
- 50 a shuttle mechanism, a thread-supplying mechanism, a lever mechanism connecting said carrier and said shuttle mechanism with respect to their lateral movements, means for driving said shuttle mechanism 110
- 55 in cooperation with said lever mechanism, means for driving said shuttle mechanism in cooperation with said driving shaft, a spring actuated rack operatively connected to said lever mechanism, a stationary knife 115
- 60 edge for normally engaging and supporting said rack, two movable knife edges capable of temporarily engaging said rack, two upright arms operatively connected to said knife edges, a lever mechanism connecting 120
- 65 both said arms for transmitting opposite 125
- movements thereto, a fork operatively connected with one of said arms, a cam on said driving shaft actuating said fork, means for the adjustment of the stroke of said fork, means for feeding the fabric in forward 70
- sewing direction, means for feeding the fabric in backward sewing direction, a lever mechanism connecting both feeding means for transmitting opposite movements thereto, a fork operatively connected to one of 75
- said feeding means, a cam on said driving shaft actuating said fork, means for the adjustment of the stroke of said fork, two separate lever mechanisms each actuating a feeding means in vertical direction, a set of 80
- selective members operatively connected to said movable knife edges, a set of members of which some are operatively connected to said first members and others with said fabric feeding means, a cam controlled member 85
- capable of engaging with either one of said second set of members and a jacquard mechanism cooperating with said selective members, as and for the purpose specified. 90
12. In a sewing-machine, the combination of a needle mechanism capable of moving across the sewing direction, a mechanism for feeding the fabric in sewing direction, a jacquard device indirectly controlling said 95
- needle mechanism and said fabric feeding mechanism, said jacquard device including a pattern chain composed of a number of cam-shaped plates linked to each other, and a polygonal drum guiding said chain, as and for the purpose specified. 100
13. In a sewing-machine, the combination of a needle mechanism capable of moving across the sewing direction, a mechanism for feeding the fabric in sewing directions, including a fixed presser foot and an adjustable presser foot and a jacquard device controlling said needle mechanism and said fabric feeding mechanism, as and for the purpose specified. 105
14. In a sewing-machine, the combination with the driving means, of a laterally displaceable needle bar reciprocated by said means, a laterally displaceable shuttle mechanism operated from said driving means, two oppositely reciprocated and vertically displaceable means for feeding the fabric in different directions, a jacquard mechanism, including a plurality of selective members, each capable of being operatively connected to said driving means and means intervening between said selective members, said needle bar, shuttle mechanism and fabric feeding means, whereby conforming with the pattern of the jacquard mechanism, the needle bar and shuttle mechanism will be displaced laterally and either one or the other of the feeding means moved vertically into operative position. 110
15. In a sewing-machine, the combination with the driving means and the stitch form- 115

ing mechanism, of a jacquard mechanism for controlling the production of stitches, said mechanism including a driven pattern chain composed of differently shaped cam plates linked together, and a plurality of pendulously supported selective members adapted to be actuated by said cam plates and capable under the action of the latter to be individually and independently brought in operative connection with said driving means and transmit movements to said stitch forming mechanism.

WILHELM BRASE.
